UNITED STATES PATENT OFFICE.

HENRY L. NEWTON, OF BUTTE, MONTANA.

PIPE-WRENCH.

No. 807,397.

Specification of Letters Patent.

Patented Dec. 12, 1905.

Application filed June 28, 1905. Serial No. 267,431.

To all whom it may concern:

Be it known that I, HENRY L. NEWTON, a citizen of the United States, residing at Butte, in the county of Silverbow and State of Montana, have invented certain new and useful Improvements in Pipe-Wrenches, of which the following is a specification.

This invention comprises a novel form of pipe-wrench, especially adapted for turning pipe or similar round bodies.

For a full description of the invention and the merits thereof and also to acquire a knowledge of the details of construction of the means for effecting the result reference is to be had to the following description and accompanying drawings, in which—

Figure 1 is a view, partially in elevation and partially in section, of a wrench embodying the invention. Fig. 2 is a view similar to Fig. 1, showing the position of the pivoted jaw in the action of turning a body in the actual use of the wrench, the handle of the wrench being broken away. Fig. 3 is a detail perspective view of the pivoted jaw. Fig. 4 is a detail perspective view of the longitudinally-movable jaw. Fig. 5 is a detail perspective view of the spring coacting with the longitudinally-movable jaw.

Corresponding and like parts are referred to in the following description and indicated in all the views of the drawings by the same reference characters.

A wrench embodying the essential features of this invention consists of a shank 1, an end portion of which is formed with a handle 2, the other end portion being provided with a longitudinal recess 3 in a side thereof. Mounted in the recess 3 is the shank 4 of a longitudinally-movable jaw 5, the mounting of the jaw 5 being such as to permit a certain amount of oscillatory movement thereof when the wrench is in actual use and in engagement with the body being operated upon. Coacting with the jaw 5 is a pivoted jaw 6, and both of the jaws 5 and 6 are provided with engaging teeth 7 upon their acting surfaces. The jaw 6 is pivoted between its ends, as shown at 8, and said jaw is provided upon its inner side with longitudinally-arranged teeth 9, said teeth 9 coacting with a number of longitudinally-arranged teeth 10 upon the shank 4 of the jaw 5. The teeth 9 are carried by the shank 11 of the jaw 6, and the jaw 6 is formed at one end of the shank 11 thereof, the opposite end of the shank 11 being curved to form an extension 12, which projects in-

wardly from the shank and operates in an end of the recess 3 in the shank 1 of the wrench. The end portion of the recess 3, in which the extension 12 operates, is undercut, as shown at 13, in order that the extension 12 may be limited thereby in its outward movement when the jaw 6 is actuated on application of the tool to a body for turning the latter. The shank 4 of the jaw 5 is loosely mounted in the recess 3 of the shank 1, and a flat spring 14 is interposed between the shank 4 and the side of the shank 1 opposite that upon which the jaw 6 is arranged. The spring 14 is held in place by a fastening, such as a screw 15, and this spring normally holds the teeth 10 of the shank 4 in engagement with the teeth 9 of the shank 11, permitting a certain amount of oscillatory movement of the shank 4 in a manner which will be obvious to those cognizant with this class of devices. A coil-spring 16 is interposed between the extension 12 and the shank 1, the extension 12 having a recess 17 and the shank 1 having a recess 18 to receive opposite ends of the spring 16 aforesaid.

It will be noted that in the practical use of the tool before set forth in this description as the jaws 5 and 6 engage the body with which they coöperate said jaws are adapted for a certain amount of oscillatory movement, and as the same are ratcheted in turning the body being operated upon the jaw 6 gets a certain amount of pivotal movement while the jaw 5 gets a similar movement, said jaw 5 being adapted to be adjusted longitudinally of the shank 1 by merely grasping the jaw and forcing the teeth 10 away from the teeth 9. The jaw 6 not only coöperates directly with the jaw 5 in the customary way, but said jaw 6 is provided with the shank 11, coacting with the shank of the jaw 5 to hold the latter at a predetermined adjustment.

Having thus described the invention, what is claimed as new is—

1. In a pipe-wrench, the combination of a shank, a work-engaging jaw pivoted to said shank, a second work-engaging jaw adjustable longitudinally of the shank, and means upon the pivoted jaw for positive locking engagement with the longitudinally-adjustable jaw to hold the latter in an adjusted position.

2. In a pipe-wrench, the combination of a shank, a work-engaging jaw pivoted to said shank, a second work-engaging jaw adjustable longitudinally of the shank and adapted for oscillatory movement thereon, and teeth

carried by the two jaws for intermeshing engagement so as to fix the position of the longitudinally-movable jaw at a predetermined adjustment.

5. In a pipe-wrench, the combination of a shank, a work-engaging jaw pivoted to said shank, and a second work-engaging jaw adjustable longitudinally of the said shank and coacting with the first-mentioned jaw, the 10 pivoted work-engaging jaw being adapted for locking engagement with the longitudinally-adjustable jaw to position the latter at a predetermined adjustment.

4. In a pipe-wrench, the combination of a 15 main shank provided with a handle, a work-engaging jaw pivoted to said shank and also having a shank, and a work-engaging longitudinally-movable jaw having a toothed shank and adapted for oscillatory movement 20 on the main shank, the toothed shank of the pivoted jaw having teeth coacting with the

shank of the longitudinally-movable jaw so as to position the latter at a predetermined adjustment.

5. In a pipe-wrench, the combination of a 25 main shank, a jaw pivoted to said shank and also having a shank, a longitudinally-movable jaw mounted upon the main shank and adapted for oscillatory movement thereon, the shank of the pivoted jaw having teeth co- 30 acting with the shank of the longitudinally-movable jaw so as to position the latter at a predetermined adjustment, and springs interposed between the main shank and the shanks of the pivotally and longitudinally 35 movable jaws.

In testimony whereof I affix my signature in presence of two witnesses.
